Atty's.

UNITED STATES PATENT OFFICE.

JAMES H. BOYE, OF CHICAGO, ILLINOIS.

KEY-HOLDER.

1,364,240.

Specification of Letters Patent.

Patented Jan. 4, 1921.

Application filed August 23, 1920. Serial No. 405,341.

To all whom it may concern:

Be it known that I, JAMES H. BOYE, a citizen of the United States, residing at Chicago, in the county of Cook and State 5 of Illinois, have invented certain new and useful Improvements in Key-Holders, of which the following is a specification.

This invention relates to improvements in key-holders, and has reference more particularly to key-holders of that type wherein the ring or loop on which the keys are strung has an opening for the application and removal of the keys, and a guard or closure member normally connecting the two 15 ends of the ring and spanning the opening. Among the salient objects of the invention are, to provide an improved key-holder of this type which may be easily manipulated for the application and removal of keys; to 20 provide an improved guard or closure which may be readily coupled to and uncoupled from one end of the ring or loop, and at the same time shall securely hold the two ends of the latter against accidental separation; 25 to provide an improved key-holder which shall be adapted to be suspended from the upper end of the pocket, thereby holding the keys off the bottom of the pocket and preventing wear upon the latter; and to 30 provide an improved suspension hook which will be securely clamped to the outer wall of the pocket and thereby prevent accidental dislodgment and loss of the keys.

With these and other objects in view, 35 which will be apparent from the following detailed description, the invention consists in the new and improved structural features and combinations of the loop, guard and suspension hook, substantially as hereinafter 40 described and pointed out in the appended claims.

In the accompanying drawing I have illustrated one practical embodiment of the invention, and referring thereto—

45 Figure 1 is a front elevation of the article, with the key-carrying loop in closed and locked position;

Fig. 2 is a similar view, showing the loop open and the suspension hook and guard or 50 coupling member swung to one side in a position to facilitate the application and removal of the keys to and from the loop;

Fig. 3 is a vertical section taken on the line 3—3 of Fig. 1; and

55 Fig. 4 is a vertical section taken on the line 4—4 of Fig. 1.

Referring to the drawing, 5 designates a

loop or open ring, the two opposed spaced ends of which are formed with round knobs or balls 6 and 7. The loop 5 is preferably 60 of steel or other elastic wire, with the balls struck up thereon, and in the normal or un-compressed position of the opposite halves of the loop, the balls 6 and 7 stand spaced apart to about the extent indicated in Fig. 2, 65 which is ample for the insertion and removal of keys over the free end 7. 8 designates as a whole the guard or coupling member which consists of a strip of elastic metal doubled transversely upon itself, the lower 70 portion of the guard being formed, by stamping, with a pair of substantially spherical sockets 9 and 10 adapted to receive the balls 6 and 7, respectively. As shown in Fig. 4, the upper portion of the 75 socket 9 is sufficiently contracted, as shown at 11, to permanently confine the ball 6 therein, but enabling the guard 8 to swing on the ball 6 in any direction. The upper portion of the socket 10 is likewise slightly 80 contracted, as shown at 12 in Fig. 3, to form a passage way or neck of a width slightly less than the diameter of the wire of which the loop 5 is made, and above the socket 10 the walls of the guard are expanded or 85 spread sufficiently to provide an easy entrance and exit passage 13 for the ball 7.

Where the key-holder is to be used in association with a suspension hook, as herein shown, the guard or closure last described 90 is formed as an integral lower end portion of a suspension hook 14. The free member or tongue 14' of this hook is formed with an outwardly bent lower end or lip 14^a which facilitates the passage of the hook over the 95 upper edge of the outer wall of a hip pocket; and to more securely clamp the hook on the wall of the pocket against danger of accidental dislodgment, I provide in the shank and tongue of the hook registering laterally 100 offset portions or hollow ribs 15 and 16, respectively, the rib 16 of the tongue normally nesting in the rib 15 of the body, as clearly shown in Fig. 3; so that when the hook is applied to the wall of the pocket, the cloth 105 of the latter is crimped between said ribs, and thereby more securely gripped than would be possible between two plain flat surfaces. The hook, of course, is made of steel or other resilient material so that the 110 tongue 14 will spring outwardly sufficiently to pass over the upper edge of the pocket, and as the hook is pushed down over the latter, the cloth is gripped between the ribs,

thus not only effecting a more secure grip of the hook on the fabric, but preventing swinging of the key-holder and keys in the pocket.

5 The normal operative position of the device is as shown in Fig. 1. To open the loop for the application and removal of keys, the loop is securely grasped by the thumb and fingers of one hand, while with the other 10 hand the hook and guard are tilted to the right, from the position shown in Fig. 1; or the hook is held rigid and the loop is tilted in the same direction. This causes the end of the loop carrying the ball 7 to rise upwardly through the contracted spring neck 12 of the socket 10 into the opening 13, out of which it instantly springs under the elasticity of the loop itself. The hook is then 15 swung to the left to about the position shown in Fig. 2, thereby leaving an ample opening for the passage of the keys.

The loop is closed by the simple reverse of these movements. The hook is swung back until the opening 13 lies directly opposite the ball 7, and the loop is compressed by 20 the thumb and finger, carrying the ball 7 into the opening 13. This done, the hook is swung back to the vertical position or the loop is swung to the left, which carries the 25 neck of the loop lying just behind the ball 7 downwardly through the contracted spring neck 12 of the ball socket, this bringing the ball 7 into full registration with its socket 10, and the loop is closed.

30 The holder, with its keys, is very easily slipped into the hip pocket by dropping it into the latter and at the same time passing the open lower end of the hook down over the upper edge of the outer wall of the 35 pocket; and in doing this, the cloth of the latter is clamped and crimped between mating ribs 15, 16, of the hook, and the latter is held against accidental dislodgment, but 40 may be readily withdrawn under a sufficient 45 pull. Obviously, so far as the described structure and functions of the loop and its guard or closure are concerned, the presence or absence of the hook is not essential, but the combined structure provides a very simple 50 and handy key-carrier not requiring a chain for purposes of safety, and holding the keys off the bottom of the pocket, with the advantages already mentioned.

Manifestly, the structural details of the 55 invention may be considerably modified from those herein shown and described without departing from the spirit of this invention, or sacrificing any of its advantages. Hence, I reserve all such variations 60 and modifications as fall within the spirit and purview of the appended claims.

I claim:

1. In a key-holder, the combination with a spring wire loop member formed with opposed spaced enlarged ends, of a guard hav-

ing a socket permanently engaged with one of said enlarged ends and another socket formed with a contracted transversely elastic neck whereby it is adapted for separable engagement with the other of said enlarged 70 ends.

2. In a key-holder, the combination with a spring wire loop member formed with opposed spaced ball-shaped ends, of a guard for separably coupling said ends, said 75 guard having on one edge a spherical socket permanently engaged with one of said ball-shaped ends, and on its other edge a spherical socket formed with a transversely elastic neck adapting it for separable engagement 80 with the other of said ball-shaped ends.

3. In a key-holder, the combination with a spring wire loop member formed with opposed spaced knobs on its ends of a guard for separably coupling said ends, said guard 85 being formed on one edge with a socket permanently engaged with one of said knobs, and on its other edge with a socket having a transversely elastic neck and with an opening to admit the other knob, whereby 90 the wire of said loop directly behind said last-named knob may be pressed through said neck to carry said last-named knob into and out of its cooperating socket.

4. In a key-holder, the combination with 95 a spring wire loop member formed with opposed spaced knobs on its ends, of a guard for separably coupling said ends, said guard comprising a transversely elastic generally U-shaped member formed with substantially 100 spherical sockets in its side walls, one of said knobs being permanently hinged in one of said sockets, and the other knob being separably hinged in the other of said 105 sockets and being insertible into and removable from the latter by reason of the transverse elasticity of said guard.

5. In a key-holder, the combination of a 110 loop member formed with spaced ends, and a suspension hook having its lower end permanently hinged by a ball-and-socket joint to one of said ends and separably hinged by a transversely elastic ball-and-socket joint to the other of said ends.

6. In a key-holder, the combination with 115 a ring to carry the keys, of a suspension hook attached to said ring, the shank and tongue of said hook being formed with laterally offset nested portions adapted to effect a grip upon the outer wall of a pocket 120 upon which said hook is hung.

7. In a key-holder, the combination with a ring to carry the keys, of a spring suspension hook attached to said ring, the shank and tongue of said hook being formed with 125 nested hollow ribs adapted to crimp between them the outer walls of a pocket upon which said hook is hung.
